S. O'HARA

PRINTING MACHINE

Filed July 8, 1927

UNITED STATES PATENT OFFICE.

SKIDMORE O'HARA, OF WALTHAM, MASSACHUSETTS, ASSIGNOR TO O'HARA WALTHAM COMPANY, OF WALTHAM, MASSACHUSETTS, A CORPORATION OF MASSACHUSETTS.

PRINTING MACHINE.

Application filed July 8, 1927. Serial No. 204,270.

The invention relates to an improvement in machines for printing. It is especially applicable to machines for printing or embossing on glass, china, porcelain, enamelled goods or other frangible articles but it is not limited to machines for printing on articles of that character. It relates especially to machines in which the printing and embossing member is reciprocable and has a printing surface on which the character, marking or design is imprinted or embossed by a die in such manner that the printing surface is adapted to imprint or emboss said design on the work, the die and the work holder being alternately brought into alignment with the printing member.

The present invention comprises a machine having a double headed reversible printing member mounted between a die and a work holder.

One object of the present invention is to provide means for actuating the work support to cause the work to engage one printing member and move both printing members as a unit until the other printing member engages the die. Another object is to provide means for reversing the positions of the printing members after each complete stroke.

The invention will be fully understood from the following description when taken in connection with the accompanying drawings and the novel features thereof will be pointed out and clearly defined in the claims at the close of this specification.

In the drawings:

Fig. 1 is a fragmentary view in side elevation and partly in diagram of a machine embodying the invention showing the several members in position ready for the printing operation.

Fig. 2 is a front elevation viewed from the left of Fig. 1.

Fig. 3 is an enlarged detail sectional view taken on line 3—3 of Fig. 1.

Fig. 4 is a fragmentary view, similar to Fig. 1, showing one printing member in contact with the work and the other printing member in contact with the inking die.

Referring to the drawings there is shown

at 10 a frame or casting to hold the working parts. Mounted in guide ways in the frame is a slideable carrier 11 on which is mounted a die 12 having formed thereon the design to be printed or embossed on the work. Said die carrier is slideable in said guideways to bring the die into and out of alignment with the printing member. Secured to the underside of said die carrier is a rack 13 which engages a gear 14 mounted on a shaft 15 which may be actuated in any suitable manner to reciprocate the said slide back and forth to move the die into and out of operative position with relation to the printing member. At 16 is shown an inking roll which will be engaged by the die 12 during its backward movement and again during its forward movement. At 17 is shown a wiper to remove the surplus ink from the die.

A double headed carrier C for the printing members is provided with trunnions 18 journaled in boxes 19, 19 which are vertically slideable on guide rods 20, 20 so that said carrier may be vertically reciprocated co-axially with the die 12 when said die 12 is in operative position as shown in Figs. 1 and 2. Said carrier has two oppositely disposed heads 21, 22 each carrying a printing member 5 which is preferably a pad adapted to take up ink from the die 12 at one stroke and at another stroke to transfer the impression to the work.

At 24 is shown a work holder and at *w* is shown a piece of work, enamelled ware or any other article to be printed in position to receive the impression from the printing member. Said work holder 24 is mounted upon a downwardly extending spindle 25 which is vertically slideable in a guide passage in the frame of the machine. It is normally held in its downward position as shown in Fig. 1 by a spring 27. Pins 28 project from the opposite side of said spindle through vertically elongated slots 9 in the sides of the guide member 29. Said pins engage with slots 30 in the arms 31, 31 of a lever 32 pivoted at 33 whereby the said spindle 25 and the work holder mounted thereon may be moved upward during the operation,

against the tendency of the spring 27 to hold the said work holder in its downward position.

Mounted on one of the trunnions 18 is a wheel 34 by which the holder C for the printing members may be rotated on its axis. It is intended that the holder C shall be rotated only through 180° at each operation so as to alternately bring the printing members 5 respectively into their upper and lower positions in direct alinement with the die 12. In order to insure the stopping of the rotation at the end of a half revolution and leave it in properly centered position a spring seated pin 6 is mounted in a slot in the side of one of the boxes 19 and the face of the hand wheel 34 is formed with two slots 7, 7 180° apart into one or the other of which said pin 6 is adapted to snap when the wheel 20 has been rotated through 180°. The said slots 7 are preferably concave and the said pin 6 is also rounded at its end so that the pins may easily ride out of the said slots by slight pressure on the hand wheel when it is desired to positively rotate said wheel thereby overcoming the spring 38 which tends to hold said pin in its locking position.

In operation, assuming the parts in the position shown in Figs. 1 and 2 the work 30 to be printed will be positioned on the work support, the die 12 having been already inked by a previous movement. By lifting up on the handle of the lever 32 the work support and the work mounted thereon will 35 be raised. After being raised a short distance the said work will come into contact with the lowermost printing member and during the continued upward movement of the said lever the said work being in engagement with the 40 lowermost printing member will cause the holder C and the guide members 19 to move bodily upward on the guide rods 20, 20 until the upper pad 5 comes into contact with the die 12. Thus it will be seen that during this 45 same upward stroke the work will receive the impression from the lower pad 5, and the upper pad 5 will be pressed into engagement with the die and receive the impression which will in turn be transferred to the next piece 50 of work at the next reciprocation. When the lever is released the spring 27 will push the pad holder 17 downward and when it has descended into the position shown in Fig. 1 the said wheel 34 may be operated to 55 turn the pad holder a half rotation reverse the positions of the two printing pads and thereby bring the freshly inked pad into position for the next printing operation and to bring the pad which has just printed into 60 position to be moved into contact with the die at the next upward stroke.

A stop mechanism is provided whereby when the pad holder C moves downward it will be limited in its downward movement, the work holder having a longer range of

movement than the pad holder so that after the pad holder has stopped the work support may be moved down a still further distance to allow sufficient clearance space for inserting and removing the work. The stop 70 mechanism provided for this purpose consists of collars 39 mounted respectively on the two guide rods 20, 20. In the meantime the work holder will have descended into the position shown in Figs. 1 and 2, carrying 75 the work holder some distance below the printing member so that the work may be readily removed and a fresh piece of work inserted on the work holder. In the meantime also the die carrier may be operated to 80 carry the die back over the inking roll and then forward again into operative position as shown in Fig. 1 ready for the succeeding printing operation. Any suitable mechanism may be provided for causing the reciprocation of the die carrier, it not being deemed necessary to show such mechanism in detail in the present drawings as that does not form a part of the present invention. 85

What I claim is:

1. In a printing machine, a die, two printing members, a holder therefor, one of said printing members being on the upper side and the other on the lower side of said holder, said holder being invertible to bring either of said printing members on the upper side, a work holder, and means for moving the work holder to press the work mounted thereon into engagement with the lower printing member and together therewith move the upper printing member into engagement with the die to receive ink from the die. 95
2. In a printing machine, a die, two printing members, a holder therefor, one of said printing members being on the upper side and the other on the lower side of said holder, said holder being invertible to bring either of said printing members on the upper side, a work holder, means for moving the work holder to press the work mounted thereon into engagement with the lower printing member and together therewith move the upper printing member into engagement with the die to receive the imprint from the die, and means for turning the holder for the printing members to bring the upper printing member to the lower position and to bring the lower printing member to the upper position. 105
3. In a printing press, a die, a vertically movable carrier having two printing members mounted thereon, one on the upper side and one on the lower side, and both normally in vertical alinement with the die, a vertically movable work holder and means to operate the work holder to press the work into engagement with one printing member and thereby also move the other printing member against the die. 110
4. In a printing machine, a die, a movable 130

holder having printing members mounted respectively on opposite sides, a movable work holder, and means for moving the work holder to cause the work thereon to engage one printing member and thereby move the holder for the printing member to cause the other printing member to engage the die to receive the imprint therefrom, said holder for the printing member being invertible to alter-
5 nate the positions of said printing members relative to the work and to the die.

5. In a printing machine, a die, two print-
10 ing members, a holder on which said printing members are mounted facing in opposite di-
rections and a work holder, said die, printing members and work holder being adapted to be brought into alinement with each other, and means for moving said work holder to move the work into engagement with one of
15 the printing members and to continue the movement to move the other printing mem-
ber into engagement with the die, said holder for the printing members being rotatable to shift the respective positions of the printing
20 members with relation to the die and the work.

6. In a printing machine, a die, a work
holder at some distance below the die, two
30 printing members mounted on a holder rotat-
able on a horizontal axis intermediate the die
and the work holder, said printing members
facing in opposite directions, means for ro-
tating said holder for the printing members
35 so as to bring one printing member in posi-
tion to face the die and the other printing
member in position to face the work, and
whereby said printing members may be re-
versed in position relative to the die and
40 work, and means for moving the work sup-
port so as to cause the work thereon to en-
gage the lower printing member to receive
the imprint and move the holder for the
printing members upward to bring the other
45 printing member into engagement with the
die.

7. In a printing press, a die, a reciprocable
work holder, a rotatable member on which
50 are mounted two oppositely disposed print-
ing members, a reciprocable carrier for said
mount, means for moving said work holder to
bring the work thereon into engagement with
one of the printing members and to thereby
55 move the said carrier and the printing mem-
bers to cause the other printing member to
engage the die.

8. In a printing press, a die, a reciprocable
work holder, two printing members mounted
60 on opposite sides of a rotatable mount for
said printing members, a reciprocable carrier
for said mount and means to operate the
work holder to press the work into engage-
ment with one printing member to receive the
65 imprint thereof and on the same stroke to
move the printing member carrier to bring

the other printing member into engagement
with the die.

9. In a printing press, a die, a reciprocable
work holder, two printing members mounted
70 on opposite sides of a rotatable mount for
said printing members, a reciprocable carrier
for said mount and means to operate the work
holder to press the work into engagement
75 with one printing member to receive the im-
print thereof and on the same stroke to move
the printing member carrier to bring the
other printing member into engagement with
80 the die, said mount for the printing members
being journaled in said carrier and rotatable
on its axis to shift the relative positions of
the two printing members.

10. In a printing press, a die and a work
holder spaced apart from each other, the
work holder being reciprocable toward and
from the die, a rotatable mount for printing
85 members intermediate the die and the work
holder, printing members mounted on oppo-
site sides of said printing member holder
whereby one of the printing members is
adapted to face the work holder while the
90 other printing member faces the die, a shaft
on which said printing members are mount-
ed, slideable bearings for said shaft whereby
said printing member holder is movable to-
ward and from the die, means whereby said
95 work holder may be moved into engagement
with one of the printing members and on the
same stroke to thereby move the other print-
ing member into engagement with the die.

11. In a printing press, a die and a work
holder spaced apart from each other, the
work holder being reciprocable toward and
from the die, a rotatable mount for printing
100 members intermediate the die and the work
holder, printing members mounted on oppo-
site sides of said printing member holder
whereby one of the printing members is
adapted to face the work holder while the
105 other printing member faces the die, a shaft
on which said printing members are mount-
ed, slideable bearings for said shaft whereby
said printing member holder is movable to-
ward and from the die, means whereby said
110 work holder may be moved into engagement
with one of the printing members and on the
same stroke to thereby move the other print-
ing member into engagement with the die,

115 said printing member holder being adapted
to be turned on its axis after a printing op-
eration to reverse the positions of the two print-
ing members so that at the next operation the
printing member which has just performed
the printing upon the work will face the die
and the printing member which has just been
in contact with the die will face the work.

12. In a printing press, a die and a work
holder, spaced apart from each other, the
work holder being reciprocable in a direction
toward and from the die, a rotatable mount

for printing members intermediate the die and the work holder, printing members on opposite sides of said printing member mount whereby one of the printing members 5 is adapted to face the work holder while the other printing member faces the die, a shaft on which said printing members are mounted, slideable bearings for said shaft whereby said printing member mount is movable to-

ward and from the die and means whereby 10 said work holder may be moved into engagement with one of the printing members and by continued movement in the same direction to thereby move the other printing member into engagement with the die. 15

In testimony whereof I affix my signature.

SKIDMORE O'HARA.
